UNITED STATES PATENT OFFICE.

EDWARD F. STRATTON AND HENRY E. DERBYSHIRE, OF PHILADELPHIA, PENNSYLVANIA, ASSIGNORS TO SANITARY COMPANY OF AMERICA, OF PHILADELPHIA, PENNSYLVANIA, A CORPORATION OF DELAWARE.

RUBBER WEDGE PAD FOR WASHBOARDS.

Application filed February 9, 1925. Serial No. 3,012.

To all whom it may concern:

Be it known that we, EDWARD F. STRATTON and HENRY E. DERBYSHIRE, citizens of the United States, residing at Philadelphia, in the county of Philadelphia and State of Pennsylvania, have invented certain new and useful Improvements in Rubber Wedge Pads for Washboards, of which the following is a specification, reference being had 10 to therein to the accompanying drawings.

This invention relates to a rubber wedge pad for washboards, and the object of the invention is the construction of a device, applied to a washboard, which will prevent 15 the washboard from being drawn outwardly or upwardly against the user, to the injury of the user during the process of rubbing or washing clothes.

Another object of the invention is the construction of a simple and efficient pad that 20 can quickly be attached to a washboard, and which pad will efficiently prevent the washboard from slipping or striking the operator as the same is in use.

25 With the foregoing and other objects in view, my invention comprises certain novel combinations, constructions and arrangements of parts as will be hereinafter described, illustrated in the accompanying drawings, and more particularly pointed out in the appended claims.

In the drawings:

Figure 1 is a perspective view of a washboard showing our devices attached thereto.

35 Figure 2 is a perspective view of a device constructed in accordance with the present invention.

Figure 3 is a fragmentary sectional view 40 of preferably a metal tub or container, showing a washboard with our devices affixed thereto in the same.

Figure 4 is a sectional view of a porcelain or other vitreous china laundry tub, 45 showing therein a washboard with our devices affixed thereto.

Referring to the drawings by numerals, 1 designates preferably a metal washtub and 2 a porcelain washtub, in each of which 50 is mounted a washboard 3.

We fasten two of our devices to each washboard, and while the devices may vary

slightly in thickness or shape, as when 55 needed to fit different shape tubs, depending upon the nature of the material from which the tub or tubs are constructed, still the same general structure is involved in each instance, and it will, therefore, only be necessary to specifically describe one of 60 the devices.

The device is preferably formed from rubber, and comprises a substantially wedge-shaped body 4, having an outer face 5 and an inner face 6. In the body, sockets 7 are provided, these sockets being formed 65 at the upper and lower ends of the body for receiving screws or nails or other suitable fastening means, whereby the device is permanently secured to the back of the washboard 1, as clearly shown in Figure 70

1. Formed in the outer face 5 of the body are a plurality of suction recesses or pockets 8, and these pockets are provided for creating a suction when the washboard is in use, as shown in Figures 3 and 4, since the 75 outer faces of the devices will be pressed tightly against the washtub during the operation of scrubbing or rubbing the clothes, whereby the washboard is held tightly in place, removing the possibility of the board 80 being pulled or otherwise forced against the body of the user to his or her injury.

These rubber wedge pads have been found to be very efficient in operation, and are 85 comparatively inexpensive to manufacture, hence making them an exceedingly desirable article of manufacture, because they fill a long needed want, both as to minimum cost and efficient results.

While we have described the preferred 90 embodiment of our invention, and have illustrated the same in the accompanying drawings, certain minor changes or alterations may appear to one skilled in the art to which this invention relates, during the 95 extensive manufacture of the same, and we, therefore, reserve the right to make such alterations or changes as shall fairly fall within the scope of the appended claims.

What we claim is:

1. A device of the class described, comprising a rubber wedge-shaped body, said body provided in its outer face with a plurality of suction recesses, and said body pro-

vided in its outer face with means for receiving fastening means for securing the body to a washboard.

2. A rubber wedge pad for washboards to be fastened directly to the back of a washboard, comprising a rubber wedge shape body having an inner smooth broad face and an outer broad face, said body having

in said outer face a plurality of suction recesses, and said body also having in said outer face and near its ends nail or screw recesses.

In testimony whereof we hereunto affix our signatures.

EDWARD F. STRATTON.
HENRY E. DERBYSHIRE.
